[57] CLAIM

The ornamental design for an electrical outlet, as shown and described.

DESCRIPTION

FIG. 1 is a front view of an electrical outlet, showing my new design;

FIG. 2 is a rear view;

FIG. 3 is a right side view;

FIG. 4 is a left side view;

FIG. 5 is a top plan view; and,

FIG. 6 is a bottom plan view.

The broken line(s) which define the bounds of the claimed design form no part thereof.
